STERILIZATION OR TREATMENT APPARATUS

Filed July 30, 1940

FIG. 2.

FIG. 1.

BY

GEORGE SPERTI.

Allen & Allen
ATTORNEYS.

UNITED STATES PATENT OFFICE

2,327,142

STERILIZATION OR TREATMENT
APPARATUSGeorge Sperti, Covington, Ky., assignor to
Science Laboratories, Inc., Norwood, Ohio, a
corporation of Ohio

Application July 30, 1940, Serial No. 348,383

12 Claims. (Cl. 250—51)

My invention relates to apparatus means and a method for the use of light sources employing an arc struck between electrodes in an envelope containing an ionized gas, and in particular to the control and operation of such devices in such a way that instant response is assured. I shall describe my invention in connection with an apparatus for the quick sterilization of glasses or other containers.

An object of my invention is the provision of means and a mode of operation whereby without the expenditure of full operating current, lamp devices may be maintained in a condition whereby the full power of the irradiation is instantly available when desired. Light sources of the type hereinabove referred to, require an appreciable time to come into operation. When a cold lamp is turned on it is necessary first to ionize the atmosphere within the lamp before the main arc discharge can be created between the electrodes. This is a matter of no consequence in continuous treatment devices; but where the use of the device is sporadic or non-continuous, it is frequently inconvenient, costly or impossible to wait at each operation for the light sources to come into full efficiency. Thus in the particular embodiment which will hereinafter be described, instant sterilization of the glasses or containers is required when they are presented to the apparatus, yet in restaurants, soda fountains and similar businesses, the use of the apparatus will be discontinuous and sporadic.

It would be uneconomical to keep the light sources in full operation at all times due to current consumption, as well as to the consequent shortening of the life of the light sources. Yet the use of the apparatus would be impractical if upon the presentation of each glass to be sterilized the operator had to wait for cold light sources to start and come up to full operating efficiency. Moreover, in a particular use which will be described, the very great number of starting operations compared with the total length of time during which the light source or sources are in full operation, would in itself cut down the useful life of the light sources.

As applied to the specific embodiment, my invention has for its object the provision of a small, neat, attractive but inexpensive sterilizer for glasses or other containers, which can be placed upon a counter, serving table or the like, and used by the regular staff of the food or beverage dispensing business with no significant loss of time.

It is further an object of my invention to provide such a sterilizing apparatus which nevertheless will be positively effective in destroying pathological and other growths of micro-organisms for the greater safety of the consuming public.

It is further an object of my invention to provide a device, the operation of which is not a matter of significant cost either as to the apparatus involved, or as to the operation thereof.

5 These and other objects of my invention which will be set forth hereinafter or will be apparent to one skilled in the art upon reading these specifications, I accomplish in that structure, assembly and mode of operation of which I shall now describe the aforesaid exemplary embodiment.

Reference is made to the drawing, wherein:

Figure 1 is a vertical section through my exemplary device.

Fig. 2 is a horizontal section taken along the 15 lines 2—2 of Fig. 1. The section line 1—1 on this figure indicates the direction of the sectional view which is Fig. 1.

Fig. 3 is an exemplary wiring diagram.

20 My invention is not limited to any particular form of envelope light source including arcs. I may employ with it, by way of example but without limitation, the type of apparatus described in my co-pending application entitled Ultra violet light source, Serial No. 350,425 filed August 3, 1940, now Patent No. 2,284,775, issued June 2, 1942, and I will describe it in this connection. However, I may use other light sources including, but again without limitation, light sources such as are described in the co-pending application of 25 John R. Stirnkorb, Serial No. 345,807 filed July 16, 1940, now Patent No. 2,307,971, issued Jan., 1943 and entitled Light sources. When light sources requiring external starting means are employed, it will be obvious to the skilled worker in the art how such starting means may be employed with such light sources from the teachings hereinafter made.

30 Briefly in the practice of my invention I provide one or more light sources (sufficient to give the strength of irradiation required), and after starting the light sources I maintain them in a condition of continuous discharge but at relatively low wattage. The wattage need only be such as to maintain the discharge with reasonable commercial certainty. In this way frequent starting is avoided and the source is maintained in a condition of continuous ionization. At the time of actual use a heavier wattage is applied to the light sources which instantly respond, as will be clear.

35 Describing the exemplary embodiment to which I have referred, as illustrated in Figs. 1 and 2, 3 represents a base which may be provided with feet 4. This base supports a housing in two parts, 5 and 5a, the parts being separable to give access to the apparatus enclosed within them. In the particular embodiment I employ a choke, both as a necessary stabilizing impedance and also as a means for varying the wattage consumed by the light sources. This choke com-

prises a core 6 on which is a winding 6a. The core may be fastened directly to the base and/or to the lower housing part 5, and may in turn support a cup shaped inner column or housing 7. The lower and open end of this housing may be flared as at 8, to approach the side wall of the housing part 5 in order to give a finished appearance. The parts thus far enumerated may be held together by bolts 9. I prefer to make the base 3 in the form of an open annulus and to cut away the central portion of the bottom of the housing part 5 so as to leave an opening indicated at 10. For cooling the choke and associated parts, this opening permits the circulation of air through the apparatus by convection.

The inner column 7 is provided with hollow arms 11, bearing sockets 12 for the light sources. The arms are so bent as to support the sockets above the top of the column 7 in such a way that the light sources 13 carried by the sockets are parallel. A bushing or bearing member 14, in the center of the top of the column 7, slidably supports a bar or shaft 15. It also engages and holds a bracket 16 within the column. To this bracket I pivot a double throw mercury switch 17 to the holder 18, on which I attach an operating member 19, on which the rod 15 may bear. The holder 18 and operating member 19 are rigid to each other and are pivoted as at 20 to the bracket 16. A coiled spring 21 may be employed to cause the operating member 19 to thrust the bar 15 upwardly. Motion of the bar 15 may be limited by pins 22 and 23.

The rod 15 carries a head 24 to which is attached an open-work engagement means 25. This engagement means may be made of wire and may comprise an outer ring and radial spokes engaging the head 24.

The top of the housing portion 6 has a central opening 26, through which the glass tumbler or other container may be passed and the open or downwardly disposed edge thereof contacted with the engagement means 25. Pushing down on the container as is now evident, throws the rod 15 downwardly thus operating the mercury switch 17.

For appearance sake, I prefer to roll the metal of the housing adjacent the orifice 26 as at 27. The housing and associated parts are decorated in any desired way. It is convenient and sanitary to cover the housing parts with Vitreous enamel to facilitate cleaning and to give a sanitary appearance. The inside of the housing should be finished as well as the outside; and it is my practice to finish all exposed metal parts, those on the inside of the housing at least, being finished in a material which is reflective to ultra violet radiation. The housing is preferably provided with a main switch 28; and electrical power may be applied to the apparatus through the usual cord 29 and plug 30, the cord passing through a bushing 31 in the housing. The nature of the electrical connections will be made clear herein-after in the description of Fig. 3.

The light sources of my co-pending application referred to above, have the advantage of small size and long life. Complete description of these light sources is not necessary here in view of the reference to the copending case. These light sources however, comprise an envelope of special glass, quartz or other substance, which either is pervious to ultra violet radiation or has a selective filtering action on some of the wave lengths of ultra violet light. Within the light sources, as diagrammatically indicated in Fig. 3,

there are interspaced electrode members 32 and 33, which are connected by a relatively heavy incandescent filament 34. Adjacent the electrodes the filament serves to heat an electron emissive substance (not shown) so as to ionize the gas within the envelope. The voltage drop across the filament keeps the electrodes 32 and 33 at a sufficient differential potential to permit the desired arc discharge. An advantage of these light sources is that they may be used in series.

In Fig. 3 one of the power leads 35 is connected through the switch 28 to one of the lamps 13. The lamps are connected so as to be in series by the lead 36. The other power lead 37 is connected to one end of the choke coil 6a. This is a tapped coil. The double throw mercury switch 17 has pairs of electrodes or contact members 38, 39, and 40, 41. When the switch is in the position shown, contacts 38 and 39 are connected together by mercury 42. The contact 38 is connected to the opposite end of the coil 6a by a lead 43, and the contact 39 is connected to the series combination of lamps 13 by a lead 44. With the switch in the position shown, it will be seen that the entire winding 6a is included in series in the lamp energizing circuit. When the switch 28 is closed, the lamps will start and an arc discharge will form in them. The arc discharge however, is operated at relatively low wattage by reason of the high impedance of coil 6a. The contact 40 is also connected to the lead 44 as shown. The contact 41 is connected by a lead 45 to the center tap of the choke.

When the mercury switch swings in a clockwise direction (through the action of the push rod 15), the electrical circuit is broken between switch contacts 38 and 39, and the mercury 42 flows to the other end of the switch and establishes a circuit between contacts 40 and 41. The impedance of the choke 6a is now diminished because current to the light sources is flowing through but a part of it. As a consequence a higher operating wattage is applied to the light sources 13. They instantly respond and the full radiation of the arcs in the tubes is instantly attained.

In use the operator will apply an inverted cleaned tumbler to the device by passing its open end downwardly through the housing orifice 26, bringing it in contact with the supporting means 25, and will press downwardly thereon. This operates the switch and instantly applies to the tumbler the full power of the ultra violet radiation. I have found that operating a pair of the light sources of my co-pending application referred to, at 8 amps., glasses, tumblers or other containers are thoroughly sterilized and all micro-organisms on their surfaces are killed by a treatment of less than one second.

Modification may be made in my invention without departing from the spirit of it. It will be for example, within the skill of the worker in the art, to employ another impedance in place of the choke coil 6a; for example, a tapped resistance, a tapped transformer or the like.

Having thus described my invention, what I claim as new and desire to secure by Letters Patent is:

1. In an ultra violet treatment device, a source of ultra violet radiation of the arc type, an impedance therefor and a source of electrical power containing said impedance, said impedance being such as to permit an arc discharge in said source, and means for causing the presentation of an

article for treatment to lessen the effect of said impedance, whereby the wattage applied to said source is increased during the time the article is so presented.

2. A mode of operation of a treatment device including an arc source of ultra violet radiation, power supply means therefor and a stabilizing impedance which comprises maintaining said arc source in a state of continuous arc discharge at relatively low wattage consumption, and causing an article presented to said means to vary said impedance, whereby to operate said arc at a different wattage to which said arc is instantly responsive.

3. In a treatment device an arc source of ultra violet radiation, power supply means for maintaining said source in a condition of continuous discharge, a controlling impedance, means to be contacted by an article presented for treatment, and means for causing said last mentioned means to vary said impedance.

4. In a device for treating articles to ultra violet radiation, an arc source of ultra violet radiation, power supply means including an impedance, means for engaging articles as presented for treatment, said last mentioned means being movable, and means actuated by the movement of said last mentioned means for varying said impedance.

5. In a treatment device an arc source of ultra violet radiation and comprising an envelope containing arc discharge electrodes, a source of power, a controlling impedance having a sufficient value to maintain the arc discharge at a relatively low wattage, and means for causing the presentation of an article for treatment to lessen the value of said impedance whereby the arc discharge is caused to take place at higher wattage with higher radiation.

6. In a treatment device an arc source of ultra violet radiation and comprising an envelope containing arc discharge electrodes, a source of power, a controlling impedance having a sufficient value to maintain the arc discharge at a relatively low wattage, and means for causing the presentation of an article for treatment to lessen the value of said impedance whereby the arc discharge is caused to take place at higher wattage with higher radiation, said impedance being a choke coil, and said last mentioned means comprising switch means for rendering part only of said choke coil effective as an impedance.

7. In a treatment device an arc source of ultra violet radiation and comprising an envelope containing arc discharge electrodes, a source of power, a controlling impedance having a sufficient value to maintain the arc discharge at a relatively low wattage, and means for lessening the value of said impedance upon the presentation of an article for treatment whereby the arc discharge is caused to take place at higher wattage with higher radiation, said impedance being a choke coil, and said last mentioned means comprising switch means for rendering part only of said choke coil effective as an impedance, said switch means being a double throw double pole switch, having two poles connected to said source and two poles connected respectively to one end and to an intermediate tab on said impedance, means actuated by the presentation of an article for treatment and a mechanical connection between said means and said switch.

8. In a sterilization apparatus for articles, a housing, an arc discharge device in said housing,

power leads for said device and an impedance of a value sufficient to maintain said device in a state of discharge at low wattage, means against which an article for treatment may be presented,

5 5 a switch, a connection between said means and said switch, and a connection between said switch and said impedance whereby to render a portion of said impedance inactive upon the actuation of said switch.

10 9. In a device of the character described, a housing, a source of ultra violet radiation, means in said housing to be engaged by the presentation of an article for treatment, power supply means for maintaining said source in a state of discharge at low wattage, and means in connection with said engagement means for increasing the wattage of said discharge upon the presentation of an article.

20 10. In a device of the character described, a base, a housing attached to said base, an impedance attached to said base and a sub-base mounted on said impedance, a source of ultra violet radiation mounted within said housing on said sub-base, means to be actuated by the presentation of an article for treatment movably mounted on said sub-base, a switch arranged to be actuated thereby and connections between said switch and said impedance whereby upon actuation of said movable means the operation of said source of ultra violet light is caused to take place at increased wattage.

25 11. In a device of the character described, a base, a housing attached to said base, an impedance attached to said base and a sub-base mounted on said impedance, a source of ultra violet radiation mounted within said housing on said sub-base, means to be actuated by the presentation of an article for treatment movably mounted on said sub-base, a switch arranged to

30 40 be actuated thereby and connections between said switch and said impedance whereby upon actuation of said movable means the operation of said source of ultra violet light is caused to take place at increased wattage, said means to be actuated upon the presentation of an article comprising a head and a slidable shaft, and said switch comprising a rockable mercury switch arranged for actuation by said shaft, said housing being perforated for the reception of said article in a position to be contacted by said head.

45 12. In a device of the character described, a base, a housing attached to said base, an impedance attached to said base and a sub-base mounted on said impedance, a source of ultra violet radiation mounted within said housing on said sub-base, means to be actuated by the presentation of an article for treatment movably mounted on said sub-base, a switch arranged to be actuated thereby and connections between

50 60 said switch and said impedance whereby upon actuation of said movable means the operation of said source of ultra violet light is caused to take place at increased wattage, said means to be actuated upon the presentation of an article comprising a head and a slidable shaft, and said switch comprising a rockable mercury switch arranged for actuation by said shaft, said housing being perforated for the reception of said article in a position to be contacted by said head,

65 70 said housing being made in two parts, and said housing being open top and bottom whereby a cooling current of air through the housing is produced by convection.

GEORGE SPERTI.
